Sarah Odabashian

UNITED STATES PATENT OFFICE.

SEROP ODABASHIAN, OF WORCESTER, MASSACHUSETTS.

BOAT.

1,244,123.

Specification of Letters Patent. Patented Oct. 23, 1917.

Application filed March 26, 1917. Serial No. 157,370.

To all whom it may concern:

Be it known that I, SEROP ODABASHIAN, a citizen of the United States, residing at Worcester, in the county of Worcester and

5 State of Massachusetts, have invented a new and useful Boat, of which the following is a specification.

This invention relates to a boat and particularly to certain novel features of construction by means of which the continued operation of the boat is rendered possible even after serious injury to portions thereof.

In a boat of the usual type, an injury below the water-line is extremely serious, 15 as repairs are difficult and the continued operation of the boat without repairs is commonly impossible or at least impracticable.

It is the general object of my invention 20 to provide a boat in which the main or body portion of the boat is rotatably mounted so that an injured portion thereof may be readily moved to a position above the water-line for repairs or removal, while an uninjured portion is simultaneously moved below the water-line in substitution for the injured portion.

A further object of my invention is to 25 provide a boat in which the power plant or engine room is mounted in fixed position within the rotatable body portion, and is protected from injury thereby.

With these general objects in view, important features of my invention relate to 30 the construction of the rotatable body member with separate detachable compartments which may be readily removed if desired, to the provision of adequate means of communication between different parts of the 35 boat, and to the provision of signaling devices by which the location of an injury to the boat may be promptly ascertained.

My invention further relates to certain arrangements and combinations of parts 40 which will be hereinafter described and more particularly pointed out in the appended claims.

The preferred form of my invention and a modification thereof are shown in the 45 drawings in which—

Figure 1 is a plan view of a boat embodying the preferred form of my invention;

Fig. 2 is a vertical longitudinal sectional view taken along the line 2—2 in Fig. 1;

55 Fig. 3 is a detail sectional view through

one of the separable compartments, taken along the line 3—3 in Fig. 1, and

Fig. 4 is a detail vertical sectional view of a modification.

Referring to the drawings, my improved boat comprises end sections 10 and 11 rigidly secured to the opposite ends of a large hollow shaft or tube 12, which extends continuously between the end sections. The sections 10 and 11 are also connected by a 60 keel 13, the sections 10 and 11, the tube 12, and the keel 13 forming a single rigid unitary structure.

An inner chamber or operating room 14 is fixed on the tube 12 near its longitudinal center. An engine or motor 15 or other suitable driving mechanism is mounted in the chamber 14, which mechanism may be connected by a transmission shaft 16 to a propeller 17, the shaft extending diagonally 70 along and across the hollow tube 12. For convenience of operation a corresponding shaft 16^a and propeller 17^a may be provided at the opposite end of the boat. Rudders 18 and 18^a are mounted at opposite ends of 75 the boat, which rudders may be operated by cables 19 extending along the hollow tube 12 to the inner chamber or operating room 14.

The parts thus far described are all fixed 80 with reference to each other and remain in fixed position during the operation of the boat.

The inner chamber 14 is inclosed by the main body member of the boat which comprises a shell 20 having an elliptical longitudinal section and rotatably mounted upon the hollow shaft or tube 12 on which it is supported by bearings 21 and 22. The outer portion of the body member is formed 90 of separate compartments 23 detachably secured to the shell 20. As shown in the drawings, each compartment is provided with a lug or projection 24 extending through an opening in the shell 20 between flanges 25 100 105 and adapted to be held in such position by a bolt 26. It will be noted that the shell 20 is spaced from the outer surface of the chamber 14, thus providing a passage or space 20^a through which access can be had to the different holding bolts 26. The compartments 23 are formed with curved sides and outer surfaces so that they may more readily resist injury from blows upon the outside thereof. This shape of the detach- 110

able sections leaves certain spaces between adjacent sections which may be closed by filling pieces 27 supported by the shell 20.

Any suitable provision may be made for 5 rotating the shell 20 and the compartments supported thereby. I have herein shown a bevel gear 28 mounted upon a motor-driven shaft 29 and engaging a ring bevel gear 30 secured to the inner surface of the shell 20. 10 With this construction it will be seen that the shell 20 and its supported compartments can be readily turned about the fixed shaft or tube 12 as an axis, and that an injured compartment can thus be readily moved to 15 the upper part of the circle, in which position it will be above water and can be readily repaired or removed.

Hand holds 31 may be secured to the outer side of each section so that they can be 20 conveniently grasped from the outside if necessary. Projections 32 may also be placed on the outer surface of the chamber 14 which will enable persons to more readily pass along the space 20^a between the chamber 14 and the shell 20. A door or opening 33 is provided at the top of the chamber 14 through which access may be secured to the space 20^a, and double doors 34 are provided from each compartment 23 to this space and 25 also from each compartment to the next adjacent compartment. An opening 35 is also provided from the chamber 14 to the hollow shaft or tube 12, and each end section may be subdivided into compartments 36 communicating with said tube.

In order that an injured compartment may be readily located I line the outer surface of each compartment with a thin metal covering 37 insulated therefrom but closely 40 adjacent thereto, said covering being connected by a wire 38 to a suitable signal drop in the chamber 14, the other side of the circuit being completed through a ground connection to the frame. If the outer surface 45 of a compartment is perforated, as by a shot or shell, a short circuit will be caused between the outer surface of the compartment and the inner covering 37, and an indicating signal will thus be given in the chamber 14.

The compartments 23 may be of considerable size, and may be used for any desired purpose, such as the transportation of merchandise or of passengers. At 23^a in Figs. 1 and 3 I have indicated a special form of 55 compartment designed for occupation by passengers. Inside of this compartment there is provided a circular recess 40, to the outer concave walls of which are secured circular tracks 41 upon which is supported 60 an inner carrier 42, which is semi-circular in cross section and which, on account of its weight, will always remain at the lowest portion of the recess 40. Rotation of the body member of the boat will therefore leave the 65 occupants of the carrier 42 undisturbed.

In Fig. 4 I have shown a slight modification of one of the end sections in which the compartments 36 above the shaft are omitted and a false cover 43 is provided to complete the conical surface of the end section. This cover portion may be readily removed, and such removal facilitates the detaching of an end compartment 23 should this become necessary. 70

Having described the details of construction of my invention it will be seen that this construction localizes the effects of any injury to the boat in such a manner that only a very general injury can interfere with the continued operation thereof. Furthermore, 80 the operating mechanism is fully protected within the sectional body member and the continued operation of this mechanism is thus assured. 75

Having thus described my invention it 85 will be evident that other changes and modifications can be made therein by those skilled in the art without departing from the spirit and scope of my invention as set forth in the claims, and I do not wish to be otherwise 90 limited to the details herein disclosed, but what I claim is:—

1. A boat comprising end sections, a fixed hollow shaft securing said sections rigidly together, an inner chamber mounted in fixed 95 position on said shaft, and a sectional outer casing rotatably mounted on said shaft.

2. A boat comprising end sections and an inner central section rigidly secured together, and a sectional outer casing inclosing 100 said inner section and angularly movable relatively thereto.

3. A boat comprising end sections and an inner central section rigidly secured together, and an outer section comprising a 105 shell and a plurality of separable compartments detachably secured to said shell, said shell being mounted for rotation around said central section.

4. A boat comprising end sections, a fixed 110 hollow tube securing said sections rigidly together, an inner chamber mounted in fixed position on said tube, an outer casing rotatably mounted on said tube, and means to rotate said casing.

5. A boat comprising end sections, a keel connecting said sections, an additional fixed axial connection between said sections, a body member formed in a plurality of separable sections and rotatably mounted on said 120 latter connection, and means to angularly adjust said body member relatively to said connection and to said end sections. 115

6. A boat comprising a fixed inner compartment, a plurality of separate outer compartments detachably secured together and inclosing said inner compartment, and means to rotate said outer compartments as a unit. 125

7. A boat comprising end sections, a fixed connection between said sections, a body 130

member rotatably mounted on said connection, and means to angularly adjust said member relatively to said connection and to said end sections, said member being composed of an inner shell and a plurality of separate compartments surrounding said shell and detachably secured thereto.

8. A boat comprising end sections and an inner central section rigidly secured together, a propeller, driving mechanism therefor mounted in said fixed central section, connections from said mechanism to said propeller, and a revoluble outer casing inclosing said central section and angularly movable relatively thereto.

9. A boat comprising end sections, a fixed hollow tube securing said sections rigidly together, an inner chamber mounted in fixed position on said tube, and a sectional outer casing rotatably mounted on said tube, said inner chamber containing driving mechanism, and a transmission shaft being provided which extends diagonally through said hollow tube to a suitable propeller.

10. A boat comprising end sections, a hollow tube and a keel, each rigidly connected to said end sections to form a unitary structure, a body member rotatably mounted on said hollow tube, and means to rotate said member.

11. A boat comprising end sections and an inner central section rigidly secured together, an outer section comprising a shell inclosing said central section but separated therefrom, means to support and rotate said shell, and a plurality of compartments detachably secured to said shell, said compartments having doors providing communication between adjacent compartments and from each compartment to the space between said shell and said central section.

12. A boat comprising a plurality of separate compartments, and means to rotate said compartments as a unit about a longitudinal axis of the boat, certain of said compartments having a rotatably mounted inner carrier, the weight whereof retains it permanently at the lowest side of said compartment.

13. A boat comprising a fixed inner compartment, a plurality of separate outer compartments detachably secured together and inclosing said inner compartment, and signal devices whereby injury to any outer compartment will be indicated in said inner compartment.

In testimony whereof I have hereunto affixed my signature.

SEROP ODABASHIAN.
